UNITED STATES PATENT OFFICE.

HARRY K. FAIRALL, JOHN D. BOLEY, AND JOHN M. CLEGHORN, OF HIGHLAND,
CALIFORNIA.

ORCHARD-HEATER.

1,080,816.

Specification of Letters Patent.

Patented Dec. 9, 1913.

Application filed October 19, 1912. Serial No. 726,676.

To all whom it may concern:

Be it known that we, HARRY K. FAIRALL, JOHN D. BOLEY, and JOHN M. CLEGHORN, citizens of the United States, residing at 5 Highland, in the county of San Bernardino and State of California, have invented a new and useful Improvement in Orchard-Heaters, of which the following is a specification.

10 This invention relates to orchard heaters and more particularly to heaters using liquid fuel, and the principal object is to provide such a heater in which water may be used and converted into steam to assist in the 15 complete combustion of the hydro-carbon fuel used.

It is also an object to provide a suitable container to separate the two fluids used, and provide separate outlets for these receptacles which open into a common casing in which the gases evolved are co-mingled and escape when ignited.

It is a further object to provide these outlets with valve controlled exits and a check 25 valve to prevent back pressure into the receptacles.

In the drawings accompanying this specification: Figure 1 is a sectional elevation of the complete structure, the burner being 30 shown entirely in elevation. Fig. 2 is a horizontal cross section on the line 2—2 of Fig. 1. Fig. 3 is a detail showing the method of connecting a generator to the container. Fig. 4 is a detail section showing 35 the connection of the second generator or exit pipe. Fig. 5 is a detail axial section of the controlling valve.

Heretofore in the operation of orchard burners, burning liquid fuel, difficulty has 40 been experienced in efficiently burning the gases evolved so that clean heat is produced, so there will be no incomplete products of combustion to settle on the foliage and discolor the fruit.

45 This invention overcomes the above difficulties in providing steam to be used in conjunction with the burning gases, so that the combustion is complete, and the full efficiency of the fuel is obtained, and no soot is 50 formed to cause injury to the trees or the fruit, and the heat is disseminated more evenly and closer to the ground by suitable deflecting means.

More specifically in the drawings, like numbers indicate the same parts in the dif-

ferent views, 6 designating a receptacle preferably and commonly formed out of sheet metal, having a partition 7 therein, dividing the container into two reservoirs which are closed by a common cover 8. This cover is 60 provided with suitable flanges so that a tight joint is formed, and prevents the evaporation of the fuel contained in one reservoir when the apparatus is not in use.

In the container two openings are provided, one in each of the respective reservoirs, into which are introduced the outlet pipes which are preferably formed in two sections; an inner section 10, and an outer section 11. These component sections are 70 practically of the same form and configuration except the means of securing the two sections together to form an outlet for the respective tanks. The inner section 10 is preferably a short elbow of suitable sized 75 pipe of non-corroding material or galvanized metal, each end being externally screw threaded, the longer end of the elbow being preferably provided with the flange 12 which is threaded thereon and adapted to 80 form the bearing for the latter against the wall 13 of the reservoir.

On the projecting outer end of the section 10, a common union 14 is threaded, this extending a sufficient distance beyond the end 85 of the pipe elbow 10 to receive the inner threaded end of the outer section 11. The elbow 10 extends a suitable distance within the tank, and its vertical leg is preferably only of such length as to receive the cap 15 90 which is provided with the orifice 16 in its end wall through which the fluid passes into the pipe. Before assembling the cap 15 on the section 10, the wire stop 17 is introduced, which forms a limit for the cork or 95 wooden check valve ball 18, this ball being contained in the valve chamber formed between the upper bend of the wire 17 and the walls of the cap and pipe. The second section 10 in the other receptacle is similarly formed with the exception that the outer clamping means is necessarily formed of one member of a coupling shown in the drawings as the threaded single portion of the coupling 19. The outer section 11 of 105 these generators or outlets is provided with a horizontal leg of any suitable length and preferably formed with the upright limb 20 at right angles to the preferably horizontal portion of this section, this limb 20 110

being extended upward to a height above the height of oil and water which will be used in the accompanying reservoir, and then bent and brought down to form the limb 21 parallel with and adjacent the limb 20, the length being such that the lower threaded end is about even with the horizontal portion and placed slightly to one side so that when the two are assembled in relation to the reservoir their ends will be as close together as the valve structure added will permit. To the lower end is secured an ordinary pipe cap 22 provided with an orifice 23 in its walls, which is adapted when 5 it is properly fitted to the threaded end of the pipe to register with the orifice 24 in the lower end of this limb 21. To provide a handle for the cap in the operation of the valve, a bore is cut through the limb, and 10 an ordinary nail 25 is introduced, or a wire of sufficient length to reach outside the inclosing casing to the generators. These two outer sections 11 are of metal pipe and of the same form, one being the hydro-carbon generator, and the other the steam generator with the exception of the slight difference in 15 the length of the horizontal limb to accommodate the slight difference in the method of coupling to their respective inner sections and the reservoir, one being capable of being threaded into the coupling 14 direct, and the other one on account of the 20 inability to turn the same, being provided with the receiving portion of the union 19. 25 Surrounding and inclosing the limbs 20 and 21 of the outlets assembled in their adjacent relation, is the inclosing member 26 preferably formed of sheet metal of cylindrical form, of sufficient diameter to form a proper heating chamber, and of sufficient 30 length as to have exit openings above the upper bend in the section 11. The lower end of the cylinder is adapted to set on the ground and is cut away at the point 27 so 35 that the cylinder will straddle the horizontal portions of the sections 11 and of sufficient height as to clear the valve handles, and not interfere with their efficient movement. 40 The upper end of the member is serrated, as shown, by a plurality of V slots 28, and the material left, preferably flared down from the apex of the serrations outward. At a proper distance below the apexes of 45 the serrations 28, a series of openings 29 are cut in the walls of the cylinder, this distance below the serrations being determined by experiment as well as the size of the orifice, the latter forming the draft opening for the entrance of air. The flaring outer 50 ends of the projections formed between the serrations, are formed as near level as possible to provide a shelf for the circular deflecting plate or cover 30 preferably of metal, and formed of considerably greater 55 diameter than the cylinder 26.

In the operation of this device oil of an inflammable nature, preferably a heavy distillate, is placed in one of the reservoirs, and water in the other, the valves 22 being opened, the pressure of the fluids is sufficient to depress the balls 17, and allow the fluids to flow to the same level in the limb 20 as in the reservoirs. A small amount of inflammable oil or hydro-carbon is now dropped on the ground within the cylinder 26 and ignited, or a torch may be used, until the gas is generated, by the vaporization of the oil in the oil limb 20. When the gas so generated escapes through the valved orifice and becomes ignited, the heat and flame will 70 pass out through the orifices 28 and under the plate 30 which is placed in position immediately after the ignition of the initial heating means. At the time when the heat is sufficient to vaporize the water in the other up-right limb, steam will issue in a stream from its orifice and co-mingling with the gases escaping from the adjacent valve will increase the draft and the breaking up of the steam into its original elements will 75 add further gases which as well known, are smokeless, and joining with the gases evolved from the hydro-carbon together with the oxygen in the air from the draft openings, results in an absolutely sootless and smokeless flame surrounding the edges of as well as in the cylinder, heating the vertical limbs 20 and 21 and continuing the 80 operation of generation, the flame issuing from the casing in the most efficient and desirable form. 85

What we claim is:

1. An orchard heater, comprising a container adapted to form reservoirs for a plurality of vaporizable fluids, pipes leading from each reservoir of said container and extending with a bend above the level of fluid in said reservoirs to terminate in valved exits placed adjacent to each other, and an inclosure surrounding said bends and their adjacent valved exits. 105

2. An orchard heater, comprising a container adapted to form reservoirs for a plurality of fluids of different characteristics, pipes leading one from each reservoir of said container, and terminating in a parallel return bend having its bend above the level of fluid in said reservoirs, and valves controlling the outlets in the ends of said pipes. 115

3. An orchard heater, comprising an apertured container for different fluids, pipes for said container means for securing said pipes to said container forming exits for fluids from said apertures, said pipes having valved extremities and a return bend in their outer portions having their loops above the level of fluid in said reservoirs and the limbs of said bend placed adjacent one another, and an apertured inclosure adapted 120 to 130

to straddle and inclose said pipes and their adjacent return bends.

4. An orchard heater, comprising a plurality of reservoirs adapted to contain fluids of different characteristics, a plurality of return bend pipes having gas generating portions, the limbs of the return bend of said pipes being placed adjacent to each other their terminal ends also being adjacent and provided with orifices, valves to control entrance of fluid into said pipes, valves to control the orifices provided for the exit of gases from the terminal end of said return bend, and an apertured closure surrounding the said return bends of said pipes.

5. An orchard burner, comprising a container divided to form a pair of reservoirs, having an aperture in the lower portion of each reservoir, a pipe elbow connected to each of said apertures, and affording an exit from said reservoirs, a check valve on the inner end of each of said pipe elbows, a return bend pipe secured to the outer end of each of said elbows, having a dependent end, valves secured one to each dependent end of said return bends having an orifice directed outwardly so that the flow therefrom will be intermediate the oppositely

disposed limbs of said return bends, and an apertured casing inclosing said adjacent return bends of said pipes.

6. An orchard heater, comprising a pair of reservoirs, each having an aperture in its lower portion, a pipe elbow connected to each said aperture and affording an exit from said reservoir, a check valve on the inner end of said pipe elbow, a return bend pipe secured to the other end of said elbow, having their return bend limbs in parallel relation and their limbs forming the dependent ends in closer relation than the other pair of limbs, a valve secured to the dependent end of each of said return bend limbs, having an orifice directed toward the oppositely disposed first limb of the other of said return bends, and a casing inclosing said return bends and straddling said pipes.

In witness that we claim the foregoing we have hereunto subscribed our names this 10th day of October, 1912.
